UNITED STATES PATENT OFFICE.

WILLIAM J. WOOD, OF PITTSBURG, PENNSYLVANIA.

WASHING-MACHINE.

SPECIFICATION forming part of Letters Patent No. 685,082, dated October 22, 1901.

Application filed September 22, 1900. Serial No. 30,764. (No model.)

To all whom it may concern:

Be it known that I, WILLIAM J. WOOD, a citizen of the United States of America, residing at Pittsburg, in the county of Allegheny and State of Pennsylvania, have invented certain new and useful Improvements in Washing-Machines, of which the following is a specification, reference being had therein to the accompanying drawings.

10 This invention relates to certain new and useful improvements in washing-machines; and it consists briefly in a body portion having a drum journaled therein and a weighted hollow rubbing-roller arranged in said drum.

15 The invention has for its object to construct a machine of this character that may be extremely simple in its construction, strong, durable, comparatively inexpensive to manufacture, and highly efficient in its

20 operation.

With the above and other objects in view, the invention consists in the novel construction, combination, and arrangement of parts to be hereinafter more fully described, and

25 specifically pointed out in the claim.

In describing the invention in detail reference is had to the accompanying drawings, forming a part of this specification, and wherein like numerals of reference indicate

30 corresponding parts throughout the several views, in which—

Figure 1 is a vertical sectional view of my improved washing - machine. Fig. 2 is a transverse vertical sectional view thereof.

35 Fig. 3 is a detail end view of the drum. Fig. 4 is a detail view of the shaft. Fig. 5 is a side view of one of the weights. Fig. 5^a is a front view thereof. Fig. 6 is a side view of the collar. Fig. 6^a is a front view thereof.

40 Fig. 7 is an end view of the weighted roller, showing the means for removing the weights.

In the drawings the reference-numeral 1 indicates suitable standards upon which the washing-machine is mounted, and 2 indicates

45 the body portion of the machine, which is formed of two sections, the upper section be-

ing indicated by the reference-numeral 3, this upper section 3 being hinged at 4 to the

lower section. In the body portion or casing

50 of the machine is revolubly mounted the drum 4', the ribs 5 of which form the rub-

bing-surface, said drum being likewise formed

in two sections, the upper section being indicated by the reference - numeral 6 and hinged together at 7.

55

The reference-numeral 8 indicates a hook pivotally secured to the upper section and adapted to engage a staple 9, formed in the lower section, and serving as fastening means to retain the sections 4 and 6 together. The 60 drum is suitably journaled at one end, as at 10, in the side of the body portion 2, and at the opposite end is provided with a shaft 11, extending through the casing and carrying an operating-wheel 12, having a handle 13. 65

The reference - numeral 14 indicates a weighted roller the ribs 15 of which form a rubbing-surface. Said roller is hollow and is provided with a rod 16, extending centrally in said roller throughout its entire length. 70

The rod 16 is provided with a number of weights 17, the latter being slidingly connected upon the rod 16 and held in position by the collars 18, carrying the set-screws 19, engaging the rod 16. The ends 14' are formed 75 in two equal halves, as shown in Fig. 7, are hinged at 16', and have a hook 16" to hold the parts in position. It will thus be seen that when it is desired to increase or decrease the weights, according to the delicacy of the 80 fabric being cleansed, it is only necessary to unlock hook 16", which permits the ends being swung apart on hinge 16', allowing the removal of shaft 16 and the adjustment of the weights. 85

The operation of my improved washing-machine is as follows: The section 3 of the casing is opened, and then the section 6 is opened for the reception of the clothes, the machine being previously filled with water 90 and soapsuds. The machine is then closed and the interior drum rotated by means of the wheel and operating-handle, thus allowing the weighted roller to revolve over the clothes, and thereby thoroughly rub and cleanse the 95 same. The clothes may also be inserted between the exterior wall of the drum and the lower section 2 of the body portion.

It will be seen that by the use of my improved washing-machine the clothes may be 100 easily cleansed and that the operation of the machine is perfectly free and easy.

After the clothes have been cleansed the machine is opened and the clothes removed

therefrom, when the operation may be repeated. Particular attention is called to the fact that the number of weights may be increased or decreased, and these weights being arranged on each end of the rod will tend to perfectly balance the roll, and the pressure of the roller exerted upon the clothes will be uniform.

It will be noted that various changes may be made in the details of construction without departing from the general spirit of my invention.

Having thus fully described my invention, what I claim as new, and desire to secure by Letters Patent, is—

In a washing-machine, the combination of a body formed in two sections and hinged together, of a rotatable drum journaled in

the lower section, said drum comprising ends, said ends being made in two parts and hinged together, ribs secured to the peripheries of said ends and having spaces between said ribs, a hollow roller placed loosely within the said drum comprising ends, ribs secured to the peripheries of the ends having spaces between said ribs, a rod mounted in the ends of the roller, weights removably mounted on said rod, and means for securing said weights in position, substantially as described.

In testimony whereof I affix my signature in the presence of two witnesses.

WILLIAM J. WOOD.
